US00D692512S

(12) **United States Design Patent**
Fanfelle

(10) **Patent No.:** **US D692,512 S**
(45) **Date of Patent:** **** Oct. 29, 2013**

(54) **GOLF PUTTING TRAINING DEVICE**

(76) Inventor: **Yves Fanfelle**, San Antonio, TX (US)

(**) Term: **14 Years**

(21) Appl. No.: **29/421,050**

(22) Filed: **May 10, 2012**

(51) LOC (9) Cl. **21-02**

(52) U.S. Cl.

USPC **D21/791**

(58) **Field of Classification Search**

USPC D21/789, 791, 792; 473/218, 251,
473/270-273

See application file for complete search history.
